US00D810312S

(12) **United States Design Patent** (10) Patent No.: **US D810,312 S**
(45) Date of Patent: **** Feb. 13, 2018**

(54) **MASSAGING DEVICE**

(71) Applicant: **GIRAFFA S.R.L.**, Milan (IT)

(72) Inventors: **Antonio Cascini**, Vimercate (IT);
Daniela De Pasquale, Milan (IT);
Davide Roncuzzi, Ravenna (IT)

(**) Term: **15 Years**

(21) Appl. No.: **35/500,912**

(22) Filed: **Apr. 13, 2016**

(80) **Hague Agreement Data**

Int. Filing Date: **Apr. 13, 2016**

Int. Reg. No.: **DM/090312**

Int. Reg. Date: **Apr. 13, 2016**

Int. Reg. Pub. Date: **May 6, 2016**

(51) LOC (11) Cl. **28-03**

(52) U.S. Cl.

USPC **D24/200**

(58) **Field of Classification Search**

USPC D24/200, 215, 214, 213, 206, 184;
D16/242; D14/426; 601/134

CPC A61H 7/001

See application file for complete search history.
